(57) **CLAIM**

The ornamental design for a cap for pipe adapter for water heater, as shown and described.

DESCRIPTION

FIG. 1 is a perspective view 1 of a cap for pipe adapter for water heater showing the present design; FIG. 2 is a perspective view 2 thereof; FIG. 3 is a front view thereof; FIG. 4 is a rear view thereof; FIG. 5 is a top view thereof; FIG. 6 is a bottom view thereof; FIG. 7 is a right side view thereof; FIG. 8 is a left side view thereof; FIG. 9 is a cross sectional view taken along line IX-IX of FIG. 5 thereof; FIG. 10 is a cross sectional view taken along line X-X of FIG. 5 thereof; FIG. 11 is a cross sectional view taken along line XI-XI of FIG. 5 thereof; FIG. 12 is a cross sectional view taken along line XII-XII of FIG. 5 thereof; and, FIG. 13 is a perspective view shown in a state of use. The evenly spaced broken lines shown in FIG. 13 depict environmental subject matter that forms no part of the claimed design.
